UNITED STATES PATENT OFFICE

162,533

RUG

Morris B. Goldfarb, Easton, Pa., assignor to Croft
Rug Mills, Inc., Easton, Pa., a corporation of Pennsylvania

Application May 29, 1950, Serial No. 10,256

Term of patent 7 years

(Cl. D92—21)

To all whom it may concern:

Be it known that I, Morris B. Goldfarb, a citizen of the United States, and a resident of Easton, county of Northampton, State of Pennsylvania, have invented a new, original, and ornamental Design for a Rug, of which the following is a specification, reference being had to the accompanying drawings, forming a part thereof, wherein the figure is a plan view of a rug showing my new design.

I claim:

The ornamental design for a rug, as shown.
MORRIS B. GOLDFARB.

Certificate of Correction

Design No. 162,533

March 20, 1951

MORRIS B. GOLDFARB

It is hereby certified that the name of the assignee in the above numbered patent was erroneously described and specified as "Croft Rug Mills, Inc." whereas said name should have been described and specified as Craft Rug Mills, Inc.; and that the said Letters Patent should be read as corrected above, so that the same may conform to the record of the case in the Patent Office.

Signed and sealed this 29th day of May, A. D. 1951.

[SEAL]

THOMAS F. MURPHY,
Assistant Commissioner of Patents.
